UNITED STATES PATENT OFFICE.

JOHN S. BARNER, OF COLVER, PENNSYLVANIA, ASSIGNOR TO BARNER RAILWAY SUPPLY COMPANY, OF PHILADELPHIA, PENNSYLVANIA, A CORPORATION OF PENNSYLVANIA.

FLUID-COMPRESSING APPARATUS.

1,372,391.

Specification of Letters Patent. Patented Mar. 22, 1921.

Application filed December 1, 1919. Serial No. 341,621.

To all whom it may concern:

Be it known that I, JOHN S. BARNER, a citizen of the United States, and a resident of Colver, Cambria county, State of Pennsylvania, have invented certain new and useful Improvements in Fluid-Compressing Apparatus, of which the following is a specification.

The present invention relates to fluid compressing apparatus and more particularly to such apparatus designed for use in connection with railway train service, the greater part of the matter disclosed herein having been described and shown in my prior application Ser. No. 266,283. For such service it is of the utmost importance that the apparatus be dependable and capable of operation without a break-down for a period of time at least equal to the run of a train. As it is against the rules to move a train if the air brake apparatus is out of order, it is the aim of all manufacturers of this apparatus to provide a construction which will not get out of operation while the train is in service. If the air brake apparatus of a train is out of order, the train cannot be moved, with the result that the track is blocked and traffic held up until the apparatus can be repaired. Such holding up of the traffic is very costly, often amounting to hundreds or thousands of dollars per hour, depending on the amount of traffic over the particular line.

The air compressing and braking apparatus as employed on railway trains at present is subject to frequent break-downs and has other defects which it is the object of the present invention to eliminate. The principal features of novelty of the present invention may be outlined as follows:

1. The apparatus produces substantially dry air at the brake valve. In present day apparatus the air delivered at the brake valve is at a temperature far above that of atmosphere. As a result when this hot compressed air expands through the brake valve, moisture is condensed out, collecting in the train pipe. This precipitation of moisture will not occur until the temperature of the air has been sufficiently reduced, which on a number of occasions has been found to be a number of cars back of the locomotive. In cold weather this precipitated moisture freezes, stopping up the pipe and rendering the brakes in rear of the obstruction useless.

This often results in loss of control of the train and in some cases has been the direct cause of derailments and wrecks. According to the present invention the air delivered to the brake valve is substantially at atmospheric temperature and has had practically all the moisture condensed out. Hence when it expands through the brake valve there is no condensation to collect in the train pipe. In other words, the compressed air discharged through the brake valve is substantially dry.

2. The compressed air delivered through the brake valve contains substantially no oil. Heretofore it has been the custom to inject oil into the compressor cylinders so that more or less oil is entrained in the compressed air and moves along with the same. In the present day apparatus, the temperature of the compressed air in the compressor is often sufficient to ignite the lubricant, and where oil refined from petroleum is used explosions have occurred, causing more or less damage. Furthermore, the temperature of the compressed air discharged from the compressor is so high that the oil entrained in the air is burned or partially consumed resulting in the deposition of carbon in the pipes. It has been found that the equalizer pipe, that is the pipe which connects the two air reservoirs of the locomotive soon fills up with partially burned products of oil so that this pipe has to be cleaned out at frequent intervals. With the present invention, no oil is introduced into the air and consequently all of the above mentioned troubles are eliminated.

3. The provision of a compressor having a relatively large capacity for its weight and size. This feature results from the novel manner of cooling the compressor and air and the arrangement whereby the pressure of the compressed air entering the second stage compressor aids the work of compressing in the low stage.

4. The provision of a compressor in which the cylinders and piston are efficiently cooled by means of air without requiring any cooling water. According to the present invention the compressor cylinders are single acting so that the atmosphere is alternately drawn into the cylinder and expelled therefrom through its open end. In this manner both the inner and outer surfaces of the

cylinder are cooled and also the interior of the piston and the piston rod.

5. The inlet and discharge valves are so disposed that the incoming cool air rushes over the valves thereby cooling the same. In the present compressor the air cylinder head has a passage through which the inlet air is drawn and the compressed air discharged, both the inlet and discharge valves 10 communicating with this passage. Hence the air drawn in on the suction stroke of the compressor comes in contact with all the valves and the surface of the passage mentioned above thereby operating to cool these 15 parts. This arrangement also eliminates burned oil or carbon on the air valves or in the air passages. The cool air drawn in on the suction stroke coming in contact with the valves and the air passages cools these 20 parts and maintains them at such a low temperature that no deposit will form and the circulation of the air through the passages tends to keep them clean. Furthermore, because the valves are maintained at a relatively 25 low temperature they may be lubricated without fear of burning out the lubricant. As a result the valve seats remain in perfect condition for an indefinite period.

6. The provision of a two stage fluid compressor having means to cool or shrink the fluid or air discharged from the first stage so that the size of the cylinder required in the second stage may be relatively small.

7. In the direct acting air compressors used on locomotives at the present time, there is considerable trouble from the breaking of the piston rods at the point where they join the pistons. The present inventor has discovered that this is due to the fact that 35 the compressed air is discharged from the compressor cylinders at one side. As the piston nears the end of its discharge stroke the compressed air near the outlet can rush out through the discharge valve, whereas the 40 compressed air caged between the piston and cylinder head at the very end of the stroke cannot escape quickly as the area open to the discharge valve is too small. The result is that the pressure on the piston at the side 45 opposite the discharge valve is greater than adjacent the discharge valve. This tends to tilt the piston and produces a bending stress in the piston rod which in a short time 50 crystallizes the part of the piston rod adjacent the piston resulting in an ultimate breaking. According to the present invention this trouble is eliminated by providing means so that at the end of the discharge stroke the pressure on the piston is always 55 centralized. This may be accomplished by discharging the compressed air centrally or 60 symmetrically with relation to the axis of the piston.

8. The compressor constructed in accordance with the present invention comprises

two end air compressors and an interposed motor, all of these parts being alined, the air compressor cylinders being connected to the interposed motor cylinder. In order that these cylinders may always remain in alignment regardless of temperature changes, the means for connecting each compressor cylinder to the motor cylinder comprises equally spaced arms. As a result all the stresses and strains, whether due to changes 75 in temperature or other causes, are centralized and there are no forces tending to throw the cylinders out of alignment.

9. One of the principal causes for breakdowns of the present day compressing apparatus is due to the burned out packing around the piston rods. In order to eliminate this defect, according to the present invention, single acting air compressors are employed so that no packing is necessary for 85 the air compressors. The interposed steam motor however, has packing around the piston rods at both its heads. But the piston rods reciprocating through this packing on the outside of the motor are brought in contact with air at atmospheric temperature so that they are kept at a relatively low temperature, and a pump constructed in accordance with this invention will operate for indefinite periods without requiring a replacement of the packing in the motor heads. Furthermore, the piston rods are properly 90 lubricated, and as they are maintained at a relatively low temperature this lubricant is not burned out or destroyed. 100

10. Heretofore it has been customary to introduce lubricant to the compressor by discharging it directly into the compressor cylinder. As a result more or less oil is carried along with the compressed air and 105 as the temperature of this air in present compressors has very often been above the flash or burning point of the oil, the oil has been destroyed with the result that the compressor has not been properly lubricated. 110 Of course as soon as the temperature of the compressor rises to the point where the lubricant is destroyed further operation causes scored cylinders and burned piston rings or piston packing, but in the present 115 invention, as previously explained, the air is maintained at relatively low temperature so that the lubricant is not destroyed. Furthermore, a novel and efficient manner of lubricating the air compressors has been devised. Thus instead of introducing lubricant with the entering air or directly into the air cylinders, with the present invention the lubricant is discharged on the non-pressure side of the air pistons. This is 120 accomplished by utilizing the discharge of steam from the tappet valves of the steam motor. This steam carries lubricant in the usual way. That is to say, a lubricant is introduced into the steam pipe leading to 130

the steam motor. Hence the steam discharged from the tappet valves carries lubricant and as this steam is directed against the interior surfaces of the air cylinders on the non-pressure side of the pistons thereof the air compressors are efficiently and thoroughly lubricated. Furthermore, the piston rods are exposed to this discharge so that they in turn are lubricated.

11. The air valves are carried in bonnets or caps secured to the cylinder heads of the air compressors. Hence if it is necessary to replace the valves or their seats become damaged, it is merely necessary to take off the bonnet avoiding the necessity of removing the entire cylinder head as where the valves are carried directly thereby.

Other objects and features of novelty of the invention will be apparent from the description taken in connection with the drawings in which:

Figure 1 is a diagrammatic view illustrating the arrangement of the air compressor and air storage apparatus on a locomotive;

Fig. 2 is a longitudinal sectional elevation through a compressor constructed in accordance with the present invention;

Fig. 3 is a sectional elevation taken substantially on the line 3—3 of Fig. 2;

Fig. 4 is a sectional elevation taken substantially on the line 4—4 of Fig. 2;

Fig. 5 is a sectional elevation taken substantially on the line 5—5 of Fig. 2;

Fig. 6 is a sectional elevation taken substantially on line 6—6 of Fig. 2; and

Fig. 7 is a longitudinal sectional elevation similar to Fig. 1 illustrating a compressor having compressing cylinders of equal size.

Referring to Fig. 1 of the drawings the compressor is illustrated as discharging through a pipe into a first reservoir, this reservoir being on the same side of the locomotive as the compressor. From the first reservoir an equalizer pipe leads to a second reservoir on the opposite side of the locomotive, from which the air is conducted through a pipe to the brake valve which controls the discharge into the train pipe.

With apparatus constructed in accordance with the present invention the air by the time it reaches the brake valve is substantially at atmospheric temperature so that practically all moisture has been condensed out in the first and second reservoirs. As a result substantially dry air is delivered through the brake valve into the train pipe.

Referring to Figs. 2 to 6 inclusive it will be observed that the compressor of the present invention in the form illustrated may comprise a steam motor A alined with and adapted to actuate a first stage air compressor B, and a second stage air compressor C. In the form shown the motor interposed between the air cylinders consists of

a cylinder 10 having a piston 11 mounted to reciprocate therein. The first or low stage compressor comprises a cylinder 12 alined with the steam cylinder 10 and provided with a cylinder head 13 closing the end opposite the steam cylinder, the end adjacent said cylinder being open. The end of the steam cylinder 10 adjacent the compressor B is closed by a head 14 and the piston rod, 15, on which the piston 11 is mounted extends through a stuffing box 16 in said head and carries a piston 17 arranged to reciprocate in the compressor 12. The peripheral wall 17' of piston 17 is extended axially in order to increase the interior surface of the piston affording a larger surface to come in contact with the cooling air, thus providing means for efficiently cooling the piston. The open end of the cylinder 10 is placed adjacent the end of the steam cylinder and is in communication with the atmosphere. As shown the head 14 of the steam cylinder is provided with equally spaced arms 18 which extend toward the cylinder 12, and at their ends carry a ring 19 which is adapted to be secured to the adjacent open end of the cylinder 12 in any suitable manner. Thus the passages such as indicated at 20 provide communication between the interior of the cylinder 12 and the atmosphere so that said cylinder and the piston 17 are cooled by the air drawn into the cylinder and expelled through the openings 20 on each stroke of the piston. As the arms 18 are equally spaced, the air and steam cylinders are always maintained in alinement, for the reason that all strains and stresses whether produced by changes in temperatures or other causes are equalized, that is to say they are transmitted from one cylinder to the other equally.

The second stage compressor C comprises a cylinder 21 in alinement with the steam cylinder 10 disposed at the opposite end thereof with respect to the first stage compressor B. The end of the cylinder 21 opposite the steam cylinder is closed by a head 22 while the opposite end, that is, the end adjacent the steam motor, is open. The adjacent end of the steam cylinder 10 is closed by a head 23 and the piston rod 15 extends through a stuffing box 24 in this head and carries a piston 25 mounted to reciprocate in the cylinder 21. The piston 25 has its peripheral wall extended axially as at 25' to increase the interior surface of the piston, as described in connection with the first stage piston. The head 23 of the steam cylinder is provided with equally spaced arms 26 which at their outer ends carry a ring 27 secured to the adjacent open end of the cylinder 21 in any suitable manner. The space between the arms 26, such as indicated at 28, provide passages so that the interior

of the cylinder 21 is always in communication with the atmosphere. Thus the interior of the cylinder C and the piston 25 are cooled by the air drawn in and expelled through the open end of the cylinder C. Furthermore, as explained in connection with the first air cylinder, the second stage cylinder C and the steam cylinder are maintained in alinement because the arms 26 connecting said cylinders are equally spaced.

Any suitable valve mechanism may be provided for admitting and exhausting steam to the steam cylinder 10 to effect a reciprocation of the piston. Preferably a control valve 29 and tappet valves 30 and 31 are employed such as described and claimed in the patent to Barner, 1,171,018, granted February 8, 1916. Steam is supplied to the control valve 29 through a supply pipe 32 and is exhausted from the control valve through the pipe 33. A lubricator 34 of the usual construction may be attached to the pipe 32 so that lubricant is supplied to the steam motor by being carried in with the entering steam. As described in the aforesaid patent the slight amount of steam caged at the opposite ends of the control valve is exhausted through the tappet valves 30 and 31. Heretofore the steam thus exhausted has been passed directly into the atmosphere. According to the present invention, however, this steam is utilized and is conducted from the tappet valves by means of the pipes or tubes 35 and 36 so that it is discharged within the cylinders B and C and preferably against the interior surface thereof. As this steam carries lubricant the interior of the compressor cylinders, pistons and piston rods are thoroughly lubricated. It will be observed that the lubricant is thus introduced to the cylinders on the non-pressure side of the pistons rather than being carried in with the inlet air to the compressors.

Referring to Figs. 2 and 3 it will be seen that the cylinder head 13 of the compressor B is formed with a fluid passage 37 which has communication with the interior of the cylinder. The head also carries the inlet valves 38 and the discharge valve 39, the latter valve controlling the discharge of fluid to the discharge pipe 40. The valves may be of any preferred type, but as shown in Fig. 2, are of the gravity puppet type and the valve 39 is positioned so that the fluid drawn in through the inlet valves 38 on the suction stroke of the compressor comes in contact with said discharge valve and also with the surface of the walls forming the passage 37 thereby cooling said valve and walls. If desired the passage 37 may be formed in and the valves carried by a removable cap or bonnet 41 secured in an opening 42 formed in the head 13. This permits the ready removal of the valves if the valve seats or valves become injured and it will be observed

further that the passage 37 is located centrally with respect to the piston 17. Hence there is no chance for the caging of air between the piston and cylinder head to produce tilting of the piston. In other words, as the compressed fluid is discharged centrally with respect to the piston the fluid pressure acting on the piston is centralized and produces no bending action in the piston rod 15.

The arrangement of the inlet and discharge valves for the compressor C is similar to that described in connection with the compressor B. As shown in Figs. 2 and 4 the head 22 is formed with a fluid passage 43 which has direct communication with the inlet valve 44 and the discharge valve 45, these valves being of any preferred type, as shown, of the gravity puppet type. The passages are constructed and the valves so located that the fluid entering through the inlet valve 44 comes in contact with and cools the discharge valve 45 and the interior surface of the walls forming the passage 43. Furthermore, the outlet passage 43 is centrally disposed with respect to the piston 25, thus avoiding any tendency to tilt the piston as explained in connection with the centrally disposed passage 37 of the low stage compressor.

In order to increase the capacity of the compressor and also to deliver a cooled compressed gas through the inlet valve 44 of the second stage compressor, an inter-cooler 36 is disposed so that the fluid discharged from the first stage compressor B is conducted to the inter-cooler through a pipe 47. The compressed gas in its passage through the inter-cooler is cooled and its volume thereby reduced and is then conducted by means of the pipe 48 to the inlet valve 44 of the second stage compressor C.

In the operation of the apparatus described above, the steam entering through the pipe 32 causes the reciprocation of the piston 11 thereby actuating the single acting compressors B and C. The fluid compressed in the cylinder 12 is discharged centrally with respect to its piston into the inter-cooler 36 and then passes through the inlet valve 44 to the second stage compressor C where it is further compressed and discharged centrally with respect to its piston through valve 45 to a pipe 49 which leads to the first reservoir shown in Fig. 1. It will be observed that the reciprocations of the pistons 17 and 25 alternately draw in and expel air from the interior of the compressor cylinders through the open ends thereof, thus cooling the compressor cylinders, piston and piston rods. A further cooling is obtained because of the arrangement of the inlet and discharge valves and the inter-cooler insures a cool charge for the second stage compressor C. Furthermore, oil laden

steam is intermittently discharged against the interior surfaces of the compressor cylinders thereby lubricating the pistons and piston rods.

- 5 In direct acting compressors of the type disclosed herein, the steam acts at full pressure throughout the entire stroke of the steam engine. Hence the total steam pressure acting on the steam piston must be greater than the resistance offered by the 10 air pistons at the end of their compression strokes. In other words, the size of the air cylinder is limited in accordance with the total steam pressure on the steam piston.
- 15 In crank driven compressors, on the other hand, the total steam pressure at the end of the stroke may be less than the total resistance to compression in the air cylinder, for the reason that energy stored up in the 20 reciprocating parts and fly wheel during the first half of the stroke is given out during the latter half and thereby aids and supplements the steam pressure.

According to the present invention, the 25 compressed fluid in the inter-cooler enters through the inlet valve to the high pressure cylinder while the piston 25 is on its suction stroke and therefore aids in moving the pistons in this direction. In other words, 30 the compressed fluid in the inter-cooler acts on the high pressure piston to aid the steam in actuating the low pressure piston on its compression stroke. Thus the steam pressure with the added air pressure on the 35 high pressure piston 25 is sufficient to move the low pressure piston during the final portion of its compression stroke although the steam pressure alone would not be sufficient to accomplish this. It therefore follows that a larger low pressure cylinder may 40 be employed with a given steam pressure than if the compressed fluid in the inter-cooler were not employed as described.

Fig. 7 illustrates a compressor similar to 45 that shown in Fig. 2 excepting that it is designed particularly for a larger quantity of compressed fluid at a lower pressure. Thus in this machine the compressor B of Fig. 2 is duplicated on both sides of the 50 steam cylinder 10. In the operation of this embodiment of the invention air is drawn into the cylinders through the inlet valves 38 and discharged through the discharge valves 39 into the pipes 45 which may lead 55 to a common reservoir. It will be observed that the compressors B are single acting and are disposed at opposite ends of the steam cylinder 10 and in alinement therewith. This construction employs the same features as described in connection with Fig. 2.

Although the present compressor has been described in connection with railway train service, it has been found that it is so efficient and dependable that it may be substituted for many of the present fly wheel

type of air compressors in stationary service. Although the invention has been described in connection with a specific embodiment thereof, it is to be understood that the invention is not thus limited but includes 70 modifications and changes which come within the scope of the appended claims.

Having thus described my invention what is claimed as new and desired to be secured by Letters Patent is:

1. A machine of the class described including in combination, two aligned single acting compressors, a double acting steam motor interposed between said compressors to actuate the latter, and means to attach 80 the compressors to the motor formed to provide communication between the interior of the compressors and the atmosphere, whereby the compressors are cooled.

2. A machine of the class described including in combination, two aligned single acting compressors including cylinders having their adjacent ends open and their outer ends closed, a double acting motor to actuate said compressors disposed between said 90 cylinders, and means to secure the open ends of the cylinders to the motor provided with passages affording communication between the interior of the cylinders and the atmosphere, whereby the compressors are cooled. 95

3. A machine of the class described including in combination, two aligned single acting compressors including cylinders having their outer ends closed and their adjacent ends open, a double acting motor interposed between said cylinders comprising a cylinder and heads, and means to secure the open end of each compressor cylinder to the adjacent head of the steam cylinder provided with passages affording communication 100 between the interior of the compressor cylinders and the atmosphere, whereby the compressors are cooled. 105

4. A machine of the class described including in combination, two aligned single 110 acting compressors and an interposed double acting motor, the non-compressing ends of the compressors being continually in communication with the atmosphere whereby air is alternately drawn into and expelled 115 from the compressors to cool the same.

5. A machine of the class described including in combination, two aligned single acting compressors, each including a hollow cylinder open at one end to the atmosphere 120 and a head closing the other end, and a motor disposed between said cylinders to actuate the compressors.

6. A machine of the class described including in combination, two single acting 125 aligned compressors and an interposed steam motor, said compressors each including a hollow cylinder having one end open to the atmosphere and a head closing the other end, and means to intermittently supply a 130

small quantity of oil laden steam from the motor against the interior surface of each compressor.

7. A machine of the class described including in combination, two aligned compressors and an interposed steam motor, each compressor including a hollow cylinder and a piston reciprocating therein, and means to intermittently supply a small quantity of oil laden steam to the interior surfaces of said cylinders to lubricate the same.

8. A machine of the class described including in combination, a fluid compressing cylinder, a piston reciprocable therein, a steam motor aligned with said cylinder including a steam cylinder, a piston reciprocable therein, a piston rod on which said pistons are mounted, means to govern the reciprocation of said steam piston including a control valve and a tappet valve at each end of the steam cylinder, and means to discharge the exhaust steam from a tappet valve to the interior surface of the compressing cylinder.

9. A machine of the class described including in combination, a double acting steam cylinder, a single acting fluid compressing cylinder aligned with the steam cylinder, one end of said compressing cylinder being open and in communication with the atmosphere, and means to secure said cylinders together.

10. A direct acting steam driven air compressor for railway use including in combination, a cylinder having a fluid passage opening from the interior thereof, and a discharge valve and an inlet valve opening directly from said passage, whereby the fluid drawn in through the inlet valve on the suction stroke comes in contact with and cools the discharge valve, inlet valve and the walls of said passage.

11. A machine of the class described including in combination, a single acting compressor comprising a cylinder having a fluid passage opening from the interior thereof, a discharge valve and an inlet valve opening directly from said passage, whereby the fluid drawn in through the inlet valve on the suction stroke comes in contact with and cools the discharge valve, inlet valve and the walls of said passage, one end of the cylinder being open and in communication with the atmosphere, and a steam motor having a cylinder aligned with the compressing cylinder, adapted to drive the compressor.

12. A machine of the class described including in combination, a double acting steam motor including a steam cylinder, a first stage fluid compressor disposed at one end of and aligned with said cylinder, a second stage compressor disposed at the other end of and aligned with said cylinder, each compressor having a fluid passage and a dis-

charge valve and inlet valve opening directly from said passage; an inter-cooler, a pipe connecting the discharge valve of the first stage compressor to the inter-cooler, and a pipe connecting the inter-cooler to the inlet valve of the second stage compressor.

13. A machine of the class described including in combination, a double acting steam motor including a steam cylinder, a first stage single acting compressor disposed at one end of and aligned with said cylinder, a second stage single acting compressor disposed at the other end of and aligned with said cylinder, each compressor having an open end in communication with the atmosphere whereby it is cooled, each compressor also having a fluid passage and a discharge and inlet valve opening directly from said passage, an inter-cooler; a pipe connecting the discharge valve of the first stage compressor to the inter-cooler and a pipe connecting the inter-cooler to the inlet valve of the second stage compressor.

14. A machine of the class described including in combination, two single acting aligned compressors and an interposed steam motor, said compressors each including a hollow cylinder having one end open to the atmosphere and a head closing the other end; and means to discharge oil laden steam against the interior surface of each compressor.

15. A machine of the class described including in combination, two aligned compressors and an interposed steam motor, each compressor including a hollow cylinder and a piston reciprocating therein, and means to discharge oil laden steam to the interior surfaces of said cylinders to lubricate the same.

16. A machine of the class described including in combination, a low pressure fluid cylinder, a high pressure fluid cylinder, an interposed steam cylinder, said cylinders being in alinement, a piston in each cylinder, a piston rod connecting said pistons, said fluid cylinders being single acting and having one end in communication with the atmosphere and said steam cylinder being double acting, an inter-cooler interposed between the discharge valve of the low pressure cylinder and the inlet valve of the high pressure cylinder, said latter valve opening on the suction stroke of the high pressure piston, whereby the fluid compressed in the low pressure cylinder acts on the high pressure piston to aid the compression stroke of the low pressure piston.

17. A machine of the class described including in combination, a single acting reciprocating compressor, a motor to drive said compressor, and means to supply lubricant to the compressor cylinder on the non-pressure side of the compressor piston.

18. A machine of the class described in-

cluding in combination, two single acting compressors, means to drive said compressors, each compressor including a hollow cylinder closed at one end and open at the other, whereby the cylinders and pistons are cooled, and means to supply lubricant to each cylinder adjacent the open end thereof.

19. A machine of the class described including in combination two aligned single acting compressors, a double acting steam

motor interposed between said compressors to actuate the latter, and means to attach the compressors to the motor formed to provide communication between the interior of the compressors and the atmosphere, said means including equally spaced arms whereby the motor and compressors are maintained in alignment.

In testimony whereof I affix my signature.

JOHN S. BARNER.
